BOOK END OR SIMILAR ARTICLE

David Greberman, Philadelphia, Pa.

Application November 27, 1946, Serial No. 135,126

Term of patent 3½ years

(Cl. D33—1)

To all whom it may concern:

Be it known that I, David Greberman, a citizen of the United States, residing at Philadelphia, in the county of Philadelphia and State of Pennsylvania, have invented a new, original, and ornamental Design for a Book End or Similar Article, of which the following is a specification, reference being had to the accompanying drawing, forming part thereof.

Fig. 1 is a front view of a book end showing my new design.

Fig. 2 is a side view of the book-end shown in Fig. 1.

I claim:

The ornamental design for a book end or similar article, substantially as shown.

DAVID GREBERMAN.
